US00D937417S

(12) **United States Design Patent** (10) **Patent No.:** **US D937,417 S**
(45) **Date of Patent:** **** Nov. 30, 2021**

(54) **FOLDABLE SUTURE NEEDLE**

Primary Examiner — Wan Laymon

(71) Applicant: **Ethicon, Inc.**, Somerville, NJ (US)

(72) Inventor: **Frank Richard Cichocki, Jr.**, Easton, PA (US)

(57) **CLAIM**

(73) Assignee: **Ethicon, Inc.**, Somerville, NJ (US)

The ornamental design for a foldable suture needle, as shown and described.

(**) Term: **15 Years**

(21) Appl. No.: **29/681,070**

DESCRIPTION

(22) Filed: **Feb. 22, 2019**

FIG. 1 is a perspective view of a foldable suture needle, showing my new design;

(51) LOC (13) Cl. **24-02**

FIG. 2 is a left side view of the foldable suture needle shown in FIG. 1;

(52) U.S. Cl. **D24/145**

FIG. 3 is a right side view of the foldable suture needle shown in FIG. 1;

(USPC **D24/145-146, 130, 133, 147;**

FIG. 4 is a proximal end view of the foldable suture needle shown in FIG. 1;

USPC **606/222-225**

FIG. 5 is a distal end view of the foldable suture needle shown in FIG. 1;

CPC **A61B 17/06066; A61B 17/06004; A61B**

2017/06071; A61B 2017/0608

See application file for complete search history.

FIG. 6 is a top plan view of the foldable suture needle shown in FIG. 1;

(56) **References Cited**

FIG. 7 is a bottom view of the foldable suture needle shown in FIG. 1;

U.S. PATENT DOCUMENTS

FIG. 8 is a perspective view of a bendable suture needle, showing another embodiment of my new design;

3,038,475 A * 6/1962 Orcutt **A61B 17/06066**

606/223

FIG. 9 is a left side view of the bendable suture needle shown in FIG. 8;

3,265,070 A 8/1966 Kurtz

FIG. 10 is a right side view of the bendable suture needle shown in FIG. 8;

4,327,655 A 5/1982 Addy et al.

FIG. 11 is a proximal end view of the bendable suture needle shown in FIG. 8;

(Continued)

FIG. 12 is a distal end view of the bendable suture needle shown in FIG. 8;

FOREIGN PATENT DOCUMENTS

FIG. 13 is a top plan view of the bendable suture needle shown in FIG. 8; and,

CN 201755238 3/2011

CN 201782788 4/2011

FIG. 14 is a bottom view of the bendable suture needle shown in FIG. 8.

(Continued)

The broken lines in the drawings form no part of the claimed design for a foldable suture needle.
